[57] CLAIM

The ornamental design for a brush for cleaning ski boots, as shown and described.

DESCRIPTION

FIG. 1 is a front elevational view of a brush for cleaning ski boots showing my new design;

FIG. 2 is a perspective view thereof, the broken line showing of a ski pole being for illustrative purposes only and forming no part of the claimed design;

FIG. 3 is an end elevational view as seen from the left of FIG. 1; and,

FIG. 4 is a top plan view thereof.

The undisclosed rear is adorned with the same surface ornamentation shown on the front and follows the contour shown from the left of FIG. 3.

FIG. 1
